UNITED STATES PATENT OFFICE.

CHARLES N. FINTON, OF LYKENS, PENNSYLVANIA.

ROPE-SOCKET.

1,387,481.

Specification of Letters Patent. Patented Aug. 16, 1921.

Application filed September 17, 1920. Serial No. 410,902.

To all whom it may concern:

Be it known that I, CHARLES N. FINTON, a citizen of the United States, residing at Lykens, in the county of Dauphin and State of Pennsylvania, have invented certain new and useful Improvements in Rope-Sockets, of which the following is a specification.

My invention relates to improvements in coupling devices for ropes and cables, and more particularly to sockets employed in this connection.

Primarily, the object of my invention is to afford facilities for securely connecting the loose ends of cables or ropes without splicing; and without resorting to sockets requiring rivets or other devices necessitating the use of special tools or appliances.

Other objects of my invention are to provide a socket without loose or detachable parts, and which, while firmly holding the rope end, does not mutilate the strands thereof and thereby weaken the rope, and at the same time to provide a socket which may be conveniently and quickly applied without the assistance of skilled help.

I attain all of these objects and other objects to become apparent in the specification following and to be specifically referred to in the claim hereto appended by the device illustrated in the accompanying drawings, in which:—

Figure 1 is an elevation of the socket ready to be affixed to a cable or rope;

Fig. 2 is a view of a socket as affixed to a rope, a portion being in section to show the tooth construction thereof;

Fig. 3 is a top view with parts of the upper clamping jaw broken away to show the insertion of the teeth into the rope; and

Fig. 4 is an end view of the socket.

Similar numerals refer to similar parts throughout the several views.

My invention relates to what may be conveniently termed a split socket, the socket being of new and novel construction. Briefly described, it comprises a socket member of suitable material, substantially U-shaped and of proper weight and dimensions, the closed end thereof being thickened to form a shank 5 to receive a link or other suitable connecting part (not shown), while the ends thereof which I call jaws are designated by the numerals 6, 6, and bendable to be clamped about the free end of a rope, indicated in the drawings by the letter A.

Each of said clamping jaws is substantially semi-cylindrical in form and constructed so that it will fit snugly about the rope to which it is to be affixed.

Upon the inner surface of each jaw are a number of oppositely arranged spaced teeth or spurs 7, preferably coniform in shape, said teeth projecting inwardly and being of a length substantially equivalent to one-half the diameter of the rope for which the socket is designed. Each jaw is cut away or beveled adjacent to the shank 5 forming an eye 8.

The free end of the rope to which the socket is to be affixed should, to prevent unraveling, be circumferentially wrapped as indicated by A'. A socket of suitable dimensions having been selected the rope is inserted into its open jaws, the wrapped extremity in close proximity with the shank 5. The jaws are then forced together closing about the rope which the coniform teeth 7 penetrate without severing or breaking the fibers of which it is composed. Insertion of the teeth forces the strands apart as illustrated in Fig. 3 and causes them to entwine about said teeth. At the same time the closure of the jaws compresses the rope into smaller compass so that a firm connection between the socket and rope is produced and accidental displacement of the socket is thus prevented. With the socket thus affixed the rope is ready for coupling.

When it is desirable to employ two sockets with a solid link intermediate thereto, it is but necessary to slip the connecting link on to the shanks of the sockets before closing the latter upon the rope ends.

It will be apparent from the drawings that the diameter of the socket when affixed decreases as it extends away from the shank 5, the tapering of the jaws toward one another being such that its diameter when closed about the rope is equal to or less at its open end, than the diameter of the rope, thus assuring an easy passage over pulleys. This construction is facilitated by the use of the circumferential wrapping of the extremity of the rope A hereinbefore described.

The teeth or spurs 7 as employed by me are substantially coniform in shape, such form being adapted to more securely engage the rope, and are capable of being readily inserted in the rope without mutilation thereto. At the same time the strain between the socket and the rope is properly proportioned,

the greater strain being toward the circumference of the rope where the teeth are of largest diameter.

Jaws 6 may be forced together by a hammer with the elimination of special dies or swedges as now generally required in applying rope sockets, and should a rope be broken the socket affixed thereto may be removed and used over again, the rope strands held 10 between the jaws of the socket being most quickly removed by burning, after which the jaws may be spread apart by inserting any available implement therebetween. Manifestly, neither skilled labor nor mechanical knowledge are necessary either for affixing the socket to a rope or removing it 15 therefrom.

The socket may be manufactured from any suitable metal, and as its construction is 20 exceedingly simple, the cost of production is necessarily small. It is obvious that a single piece of metal may be used by flattening it at its ends and then bending it into shape.

While I have illustrated and described the 25 preferred form of my invention, no limitation or restriction is intended to be made, as changes and modifications within the scope of the claim are to be resorted to when desired.

Having thus described my invention, what I claim is new and desire to secure by Letters Patent, is:—

A one piece rope socket comprising a pair of complementary and opposed substantially semi-cylindrical jaws of uniform thickness, coniform teeth projecting inwardly from said jaws, and an integral and flexible shank connecting the jaws at one end and of such length that when the jaws are forced together to grip the end of a rope a tapered socket will be formed having its greater diameter adjacent the curved shank, such tapered socket coöperating with the teeth to prevent the rope from pulling out of the 45 socket.

In testimony whereof I affix my signature.

CHARLES N. FINTON.
